RAILWAY VEHICLE UNDERFRAME CONSTRUCTION

Jack W. Borger, Chicago, and William Van Der Sluys,
Homewood, Ill., assignors to Pullman Incorporated,
Chicago, Ill., a corporation of Delaware

Filed Feb. 23, 1965, Ser. No. 434,517
1 Claim. (Cl. 105—422)

The present invention relates to railway vehicles and more particularly to a new and improved underframe and floor structure for a passenger railway vehicle.

It is an object of the present invention to provide a passenger railway vehicle with a floor arrangement which is constructed and arranged to resist the tensile stresses when the vehicle is subjected to bending under load.

It is a further object to provide a passenger railway vehicle floor arrangement including a plurality of small sections constructed and arranged such that the transverse junctures of the sections lie along lines substantially coinciding with the lines of contraflexure of the characteristic bending moment curve of the vehicle.

It is still a further object to provide a passenger railway vehicle floor arrangement formed of a plurality of floor sections of a length which continuously spans the portion of the floor which is subject to bending under load and which sections are arranged so that the abutting transverse edges thereof lie substantially along the lines of contraflexure of the characteristic bending moment curve of the vehicle.

It is another object to provide a passenger railway vehicle with a new and novel side sill structure which facilitates the installation of the flooring into the underframe.

A feature of the present invention is the provision of a floor panel structure which provides insulation and is substantially devoid of warpage caused by temperature and humidity changes.

In the drawings:

FIG. 1 is an elevational view of the underframe of a railway vehicle embodying the structure of the present invention with only a portion of the outside side sill being shown for the purpose of illustrating underlying details of structure.

FIG. 2 is a fragmentary plan view of the railway vehicle of FIG. 1 with some of the parts being broken away to show underlying details of structure.

FIG. 3 is a cross-sectional view taken generally along the lines 3—3 of FIG. 2 and showing the typical juncture of the transverse abutting edges of the floor sheets.

FIG. 4 is a cross-sectional view taken generally along the line 4—4 of FIG. 2 and showing the juncture of the floor sheets along the longitudinal abutting edges.

FIG. 5 is a cross-sectional view taken generally along the line 5—5 of FIG. 2 and showing the side sill of the present invention and the manner in which the outer longitudinal edge of the flooring is supported thereon.

FIG. 6 is a cross-sectional view taken generally along the line 6—6 of FIG. 2 and showing the manner in which the flooring is supported at the end sill.

FIG. 7 is a schematic illustration of the underframe and floor arrangement and having superposed thereon the typical bending moment curve of the vehicle under load.

Referring now to the drawings, the present invention is embodied in a railway car underframe 10 comprising essentially a pair of laterally spaced and longitudinally extending side sills 11 to the outer ends of which there are fixed end sills 12. Spanning the side sills 11 and fixed

2

thereto are bolsters 13 which are connected to the adjacent one of the end sills 12 by center sills 14. Spanning the side sills 11 between the bolsters 13 is an intermediate floor support structure 16 including transversely extending cross-bearers 17 and longitudinally extending members 18 fixed between the cross-bearers 17. The outer ends of the underframe between the bolsters 13 and end sills 12 include end frame floor support structure 19 and 20. Disposed and supported on the intermediate and end frame supporting structures 16, 19 and 20 are floor panels of planks 21—21, 22—22 and 23—23.

The side sills 11 as shown in particular in FIG. 5 may be formed of two components including an inner or inside sill member 26 which may be formed as a right angular member including a horizontal leg 27 and a vertical leg 28. The inside sill member 26 is preferably formed from steel. Fixed to the outer face of the vertical leg 28 is a downwardly depending vertical member 29 of an outside sill member 31. Extending inwardly from the vertical leg is a horizontal leg 32 which is arranged to lie substantially coplanar with the top surface of the floor planks 21—21, 22—22, and 23—23. The outside sill member 31 is preferably formed from aluminum and may be contoured to impart an attractive outer appearance to the vehicle. The inside and outside sill members 26 and 31, respectively, are sized so as to be capable of assuming the loads imposed thereon during use of the railway vehicle. As more fully to be explained hereinafter, the outside sill member 31 is fastened or assembled to the inside sill member 26 by means of fasteners 34 or the like after substantially the entire underframe has been assembled. Depending downwardly from and fixed to the horizontal leg 27 of the side sill member is a body skirt 36 which may be formed of a light weight material such as aluminum or the like. Extending lengthwise along the bottom of the body skirt 36 is an angle member 37 which is suitably fastened to the underside of an inwardly extending horizontal limb or flange 38. Suitable vertical bracing 39 may be selectively spaced lengthwise of the body skirt 36 and fixed along the vertical edges between the vertical web 41 and the upright leg 42 of the angle 37 and along the horizontal edges between the flange 38 and flange 40 of the skirt 36.

As shown, particularly in FIGS. 1, 4 and 5, the cross-bearers 17 are formed as a substantially channel shaped member including a vertical web 43 from the upper and lower edges of which there extend upper and lower horizontal webs 43a and 45, respectively. The ends of each of the cross-bearers 17 are fixed to the inside sill members 26 prior to the assembly of the outside sill member 31 to the former. As shown in FIG. 5 the outer terminal vertical edge of the cross-bearers 17 abuts against the vertical web 28 of the inside sill member 26 and is fixed thereto as by welding. The lower cross-bearer horizontal web 45 is supported on the horizontal leg 27 and is fixed thereto also as by welding. The assembly of the cross-bearer and the side sill is facilitated by the fact that the outside sill member 31 is not attached to the inside sill member 26 at this time.

The center sills 14 extending between the bolsters 13, which are formed with a substantially box like section, and end sills 12 at each end of the vehicle 10, each comprises essentially a pair of transversely spaced channel members 44. Disposed and fixed on the center sill members 14 on the right end of the car as viewed in FIG. 2 is the end frame floor support structure 19 which comprises essentially a longitudinally extending plate 46 in-

termmediate the channels 44 and having one end fixed at one end to the bolster 13 and at the other end to the end sill 12. Supported on the longitudinally extending plate 46 in a manner so that the upper surfaces thereof are substantially coplanar is a transversely extending plate 47 which is fixed at its ends to the channels 44. The transverse plate 47 may be provided with a cutout for accommodating the drawbar mechanism (not shown).

At the left end of the railway vehicle 10 the frame support structure 20 includes a longitudinally extending plate 46 fixed at one end to the bolster 13 and at the other end to the end sill 12. The left end of the vehicle as shown may not be provided with a drawbar such that the drawbar plate 47 may be eliminated. Substituted therefor are a pair of lengthwise spaced transversely extending plates 49 which span and are fixed at their respective ends to the channel members 44. The longitudinal plate 48 and transversely extending plates 49 are arranged so as to lie substantially in the same plane and provide a substantially uninterrupted floor supporting surface.

The floor panels or planks 21-21, 22-22 and 23-23 are of substantially identical construction differing in respect of length for reasons which will become more apparent hereinafter. The planks comprise a core 51 made from a light weight material such as balsa wood. Adhered to the top and bottom surfaces of the balsa wood core as by bonding with a suitable adhesive, is a thin metallic plate 52 which may be aluminum or the like. Preferably the materials employed are such as to result in a light weight structure providing maximum strength. The use of the preferred materials of aluminum and balsa with the aluminum sheets adhered to the top and bottom surfaces of the balsa core 51 also achieves a floor which is substantially free of warpage which may result from temperature and humidity changes. At the same time the floor structure is of sufficient strength to absorb some of the tensile stresses applied to the vehicle when loaded. To obtain the maximum benefit from this characteristic of the floor structure, the sheets are formed and dimensioned such that the length falls along the transverse lines of contraflexure of the characteristic bending moment curve of the vehicle under load.

As shown in particular in FIGS. 2 and 4 the intermediate floor structure 16 comprises the cross-bearers 17 and the longitudinally extending members 18 which are fixed at their ends between adjacent ones of the cross-bearers 17 or to the bolster 13. The longitudinal member 18 comprises essentially a channel member having a vertical web 53 from which there extend upper and lower horizontal webs 54 and 55, respectively. The upper web 54 is cut away at its point of attachment to the cross-bearer 17 so that the vertical web 53 abuts against the horizontal web 43 of the cross-bearer 17 and is fixed thereto as by welding. The cut-away portion defines a terminal edge on the upper horizontal web 54 which is fixed to the terminal edge of the upper web 43a of the cross-bearers as by welding. In this manner the intermediate support horizontal webs 54 and the horizontal cross-bearer webs 43a are substantially coplanar to provide a level support surface for the floor planks adapted to be supported thereon.

As is well known, the bending moment characteristics of a railway vehicle under load are readily predictable. Such bending moment characteristics are of significance in determining the failure characteristics of the vehicle. Typically, as shown in FIG. 7, the characteristic bending moment curve *c* results in two points or transverse lines *a* and *b* of contraflexure or zero bending lengthwise of the car and which normally occur somewhat inwardly of the bolsters 13. The remainder of the vehicle is subject to bending as shown resulting in the creation of tensile stresses in the vehicle. Heretofore it has been common practice to form the floor planks of small sections which were indiscriminately placed so that the floor was incapable of imparting substantial strength to the vehicle,

particularly in absorbing the tensile stresses resulting from the bending under load. In accordance with the present invention the floor planks 21-21, 22-22 and 23-23 are formed of a sufficient length so as to continuously extend between the lines of contraflexure of the car and thus are capable of assuming some of the tensile stresses imparted on the car during bending. As shown, planks 21-21, 22-22, and 23-23 are arranged so that the abutting edges of the planks 21 and 22 and the abutting edges of the planks 22 and 23 lie along the respective lines of contraflexure *a* and *b*. Conveniently, the cross-bearers 17 are spaced and located so that one lies along each of the lines of contraflexure. Moreover, there are two sets of floor planks employed; one set 21, 22 and 23 lying on one side of the intermediate or longitudinally extending members 18 and 46 and the other set 21, 22 and 23 on the opposite side thereof.

The adjoining longitudinal edges of the planks 22-22 as shown in FIG. 4 are fixed to the intermediate member 18 as by fastening studs 56. The adjoining longitudinal edges of the planks 21-21 and 23-23 which overlie the end frame supports may be fastened similarly to the members 46. As shown in FIG. 5, the outer longitudinal edges supported on the side sills 11 are supported on a Z-angle 57 which includes a horizontal leg 58 fixed to a vertically depressed section 59 formed adjacent the end of the cross-bearer 17. The outer longitudinal edges of the planks 21, 22 and 23 are placed in close proximity to a vertical web 61 of the Z-angle 57 which terminates at its upper end in a horizontal extending flange 62. The horizontal flange 62 is arranged to support the horizontal leg 32 of the outer side sill member 31 substantially coplanar with the upper surface of the planking 21, 22 and 23.

For providing reinforcement to the horizontal flange 58 there may be provided a plurality of lengthwise spaced gusset angles 63 having leg 64 fixed as by welding to the horizontal web 43 of the cross-bearer 17 and a leg 66 disposed between the terminal edge of the cross-bearers 17 and the vertical leg 29 of the outside sill 31. The gusset angle 64 extends upwardly and underlies the horizontal leg 58 of the Z angle 57.

As shown in FIG. 6 the end planks 21 and 23 may each be supported along the outer edges adjacent to the end sills 12 on the horizontal leg 67 of an angle member 68 having a vertical leg 69 fastened as by welding to a vertical plate 71 of the end sill 12. The angle 68 is located so that the upper surface of the outer planks 21 and 23 is substantially coplanar with the upper surface of the end sills 12. Filling the voids at the lines of transverse and longitudinal juncture of the planks 21, 22 and 23 with each other and with the frame members is a suitable mastic 72.

From the foregoing description it should be readily apparent that with the floor planks 21-21, 22-22 and 23-23 attached to the underframe and sized so as to span the lines of contraflexure *a* and *b*, during bending under load, the planking will assist in strengthening the underframe. Moreover, the strength of the underframe is increased by a minimum increase in weight for the reason that the floor planks are constructed of the relatively lightweight balsa wood and aluminum sheet construction. This floor construction is further advantageous in that it does not warp when subjected to temperature and humidity changes as do many of the other types of known floorings constructions.

What is claimed is:

A railway vehicle underframe comprising two transversely spaced side sills extending lengthwise of said vehicle, lengthwise spaced bolsters fixed between said side sills inwardly of the ends thereof, end sills fastened across the respective ends of said side sills, said side sills each including an inner sill member and an outer sill member, said inner sill member having an inwardly extending horizontal leg and an upwardly extending vertical leg, said

outer sill member including a downwardly depending web overlying and fixed to said upwardly extending vertical leg of said inner sill member, said outer sill further including a horizontal web projecting inwardly from the upper end of said vertical web, a floor support structure including a plurality of cross-bearers spaced lengthwise of said vehicle, said cross-bearers being fixed at the ends thereof to said inner sill members of said side sills, and floor planks supported on said cross-bearers, said floor planks being of a thickness to lie substantially coplanar with said horizontal webs of said outer sill member.
